Primary Examiner — Susan E Krakower*Assistant Examiner* — Jerry Shiuan-Hua Hsu(74) *Attorney, Agent, or Firm* — Calfee, Halter & Griswold LLP(57) **CLAIM**

I claim the ornamental design for a check valve, as shown and described.

DESCRIPTION

FIG. 1 is a rear perspective view of the check valve;
FIG. 2 is a front perspective view thereof;
FIG. 3 is a top plan view thereof, the bottom plan view being identical thereto;
FIG. 4 is a right side elevational view thereof, the left side elevational view being identical thereto;
FIG. 5 is a rear elevational view thereof; and,
FIG. 6 is a front elevational view thereof.
The broken lines illustrate portions of the check valve which form no part of the claimed design.
